UNITED STATES PATENT OFFICE.

HENRY VINCENT JAMES, OF RADLETT, ENGLAND.

PAPER-WEB-CONTROL DEVICE FOR REEL-FED ROTARY PRINTING-MACHINES.

1,263,419.

Specification of Letters Patent. Patented Apr. 23, 1918.

Application filed January 29, 1916. Serial No. 75,112.

To all whom it may concern:

Be it known that I, HENRY VINCENT JAMES, a citizen of the United Kingdom of Great Britain and Ireland, and resident of 5 "Cintra," Aldenham avenue, Radlett, in the county of Herts, England, have invented certain new and useful Improvements in Paper-Web-Control Devices for Reel-Fed Rotary Printing-Machines, of which the following is a specification, such as will enable others skilled in the art to which it appertains to make and use the same.

This invention relates to the feeding of printing presses with paper at a feed tension 15 particularly referring to rotary presses used for the printing of newspapers and similar products, in which a number of actual printing portions are frequently employed as one complete unit fed from a number of paper 20 reels, and in which the paper feed tension of each web must be maintained practically constant at all printing speeds though at various feed tensions when so employed in multiple, according to press requirements. 25 This paper web feed tension is generally obtained by application of a brake to the paper feed reel, and in my application for United States Letters Patent Serial Number 34757, filed June 17, 1915, I have shown how 30 an automatic electro-dynamic braking system may be so applied, and in my later application for United States Letters Patent Serial Number 71451, filed Jan. 11, 1916, I describe a satisfactory method of obtaining 35 a paper web feed tension for such printing presses by means of a tension device applied directly to the paper web after it is unwound from the reel, such device being placed between the paper feed reel and the 40 printing cylinders of the press.

In my said application for United States Letters Patent Serial No. 71451, I describe a mechanical means of gripping the feeding paper web, placed between the paper reel 45 and the printing press cylinders, consisting as an example of rubber covered rollers between which the paper web is passed and frictionally gripped.

The present invention consists in the combination and arrangement of a frictional paper web gripping device and an electro-dynamic braking system applied thereto, for the purpose of obtaining a paper web feed tension to the printing cylinders. For 55 the purpose of simplifying the description I will refer to parts similar to those shown

in the cited earlier applications and particularly to the arrangement shown in Fig. 2 of No. 34757 and Figs. 1 and 2 of No. 71451.

I will describe the new combination and invention briefly as follows:—the electro-dynamic braking element referred to in number 34757 as element No. 1 is suitably mechanically coupled to the paper web gripping device described in No. 71451, for the purpose of retardation and braking of same,—the electro-dynamic machine referred to as element No. 2 is suitably mechanically coupled to the main driving gear of the printing press, and a means is provided for regulating the energy in the circuits of the armatures.

I will give the following description as an example of one method of putting my invention into effect and make reference to the accompanying drawings in which Figure 1 diagrammatically illustrates same, referring to one reel and press only, Fig. 2 is a diagrammatic representation of the connections of the power elements; and Figs. 3 and 4 illustrate roller gripping devices similar to those illustrated in my cited application No. 71451. For the gripping device I employ two rollers T and T¹ each having parallel rubber faces over a part of their length 85 fully equal to the maximum width of the paper web and shafts P and P¹ extended at both ends, and mount them at a convenient position on the press between the paper reel a and the printing cylinders of 90 the printing press by carrying their shafts in ball bearings B, the bearings of the roller T¹ being fixed and those of the roller T carried in a bearing block B¹ slidable on guides G allowing of position adjustment, 95 but all carried in the press frame sides, and in such a manner that the rubber faces of the rollers will be normally parallel to the faces of the printing cylinders.

Attached to each bearing of Roller T, I 100 mount an adjustable tension spring Z by means of which pressure may be obtained and adjusted on the paper web between the rollers for the purpose of securing the required paper web feed tension to the cylinder when the roller T¹ is braked by means of the electro-dynamic machine M.

I also mount a lever cam L on a shaft L¹ passing through a bore in the outer end of a rod L² secured to the block B¹ by means 110 of which the roller T may be lifted and held clear of roller T¹ for the purpose of

readily threading the paper web between the rollers during the processes of sheeting up and general make ready of the press.

- As shown in Fig. 1 at a conveniently near point to the rollers I mount an electro-dynamic machine M which I will refer to as power element No. 1 and mechanically couple its armature shaft n to the extended shaft p^1 of the roller T^1 in a manner and 10 through gear g of such a ratio that at maximum press speed with full field magnet excitation it will develop a pre-determined maximum electro-motive force across its armature say 200 volts. I mount a second 15 electro-dynamic machine M^1 which I will refer to as power element No. 2 at any convenient position and mechanically couple its armature shaft N^1 to any convenient shaft of the actual printing press in such a manner and through gear g^1 of such a ratio that 20 at maximum press speed with full field magnet excitation it will develop an electro-motive force equal to that of the No. 1 power element at maximum press speed, say 25 also 200 volts.

I electrically connect the field magnet circuits F and F^1 of power elements M and M^1 respectively, to the supply mains S and obtain normal excitation.

- 30 I electrically connect the armatures N and N^1 of the No. 1 and No. 2 power elements respectively and a suitable variable ohmic resistance r all three in series across the supply mains, the two armatures in such 35 a manner that when the No. 1 power element coupled to the roller T^1 is driven thereby, it will develop an electro-motive force tending to boost up the voltage of the supply mains, and the No. 2 power element, 40 in such a manner that in operation as described, it will tend to set up an electro-motive force in opposition to the supply mains.

The two electric power elements M and 45 M^1 are in no manner directly associated with the driving of the printing press and their action relative to the main driving source is as follows: With the press at rest and a source of energy from the supply 50 mains S feeding the electric power elements M and M^1 they both tend to become simple power driving elements, elements M tending to turn the roller T^1 in a direction of rotation which will tighten the web between 55 the printing cylinders and roller T^1 and the element M^1 tending to turn the printing cylinder to which it is coupled by gear g^1 in the direction of its normal rotation in the process of printing, that is, it will tend 60 thereby to drive the printing press. In this manner the correct feed web tension is maintained by element M with the press at rest, and the tendency of element M^1 to move the press is a negligible quantity.

- 65 When the press is driven by the main

power the conditions in element M and M^1 change—element M is driven by roller T^1 and is so electrically connected as to its field and armature that it becomes a generator, and generates an electromotive-force of like 70 directions as that of the supply mains S and so boosts up the voltage of the latter,—and element M^1 is so electrically connected as to its field and armature that it operates as an electric motor and assists in driving the press, and sets up an electro-motive force of opposite directions to that of the supply mains S—and elements M and M^1 are so geared to the press through gears g and g^1 that their speeds at all times correspond with one another. The electro-motive force in each armature is likewise at all times and speeds equal, but of opposite directions, the one thereby equalizing and at all times neutralizing the other, with a result that the voltage of the supply mains S is at all times and speeds the effective electro-motive force through the circuit of the armatures of the elements M and M^1 and the regulating resistance r , resulting in the 80 ohmic value of the latter at all time determining the energy in the circuit of the armatures and the corresponding braking effect transmitted from element M through gear g and roller T^1 to the paper web.

It will be obvious therefore that at all press speeds, and if desired with the press at rest, the feed web tension will correspond to the energy in the circuit of the armatures M and M^1 regulated only by the ohmic 100 value of the resistance r .

The field and armature windings of both elements M and M^1 in Fig. 1 are diagrammatic only. The speeds of roller T^1 and the press cylinders at all times correspond to 105 one another and the paper feed speed, and likewise to the armatures of elements M and M^1 .

Under printing conditions, the paper web will be pulled into the printing press by 110 the impression cylinders and likewise the paper web as it passes between the rubber covered rollers will transmit power to roller T^1 at a speed corresponding to the press speed and likewise the roller T^1 115 will also drive the armature of the No. 1 power element M correspondingly, and further that the armature of the No. 2 power element will rotate with the press at a corresponding speed, and that No. 1 power element will become a generator and develop a like direction of electro-motive force as that of the supply mains, and that the No. 2 power element armature will develop power energy in the direction of driving the 120 printing press and set up an electro-motive force in opposition to that of the supply mains, and that as the electro-motive force developed by both armatures will at all 125 times be of like value of electro-motive force 130

though of opposing directions, the effective electro-motive force of the circuit inclosing the two armatures and the variable ohmic resistance r will at all speeds be equal to that of the supply mains and the energy in the circuit correspond to the ohmic value of the variable resistance, and that a dynamic brake will be developed by the No. 1 power element accordingly, which will be transmitted to the paper web through the rubber covered roller T^1 and a constant web tension be developed correspondingly at all press speeds. Either electric power element may be used in multiple but it would be necessary to employ one No. 1 power element, reference M , for each independent braking device it is only necessary however to employ one No. 2 power element, reference M^1 , regardless of the number of No. 1 power elements.

What I claim and desire to secure by Letters Patent is:—

1. In an electro-dynamic braking system for a paper web gripping and feed tension device for a reel fed rotary printing press, the combination of an electricity supply circuit inclosing the armature circuits of two electric power elements electrically connected in series, one element mechanically cou-

pled to the paper web gripping and feed tension device and electrically connected to develop a like direction of electro-motive force as that of the supply circuit, and the other power element mechanically coupled to a shaft of the main driving gear of the printing press, and electrically connected to develop an electro-motive force in opposition to that of the supply mains, and means for varying the energy in the circuit of the armatures of the electric power elements.

2. Braking apparatus for use with paper printing machines between the feed reel and the printing press, said apparatus comprising a paper web gripping device consisting of two parallel rollers one of which is coupled to an electric power element, a second electric power element coupled to the printing press, an electrical connection coupling the armatures of the two electric power elements in series across the electricity supply mains whereby the said power elements will develop opposing electro-motive forces.

In witness whereof I have hereunto set my hand in presence of two witnesses.

HENRY VINCENT JAMES.
